FOLDING CASE

Filed Aug. 23, 1928

Inventor
Alpha K. Metcalf
by Noratio E. Bellows
attorney

UNITED STATES PATENT OFFICE.

ALPHA H. METCALF, OF ATTLEBORO, MASSACHUSETTS, ASSIGNOR TO SAART BROTHERS COMPANY, A CORPORATION OF RHODE ISLAND.

FOLDING CASE.

Application filed August 23, 1928. Serial No. 301,550.

My invention relates to a foldable case or container for automobile registration certificates, drivers' licenses, and other flexible documents.

5 The essential objects of my invention are compactness; convenience of transportation; protection of the contents against creasing and from the elements; facility of opening and closing the case; ease of insertion and 10 removal of contents; security against accidental escape of the latter; and simplicity and inexpensiveness of construction.

To the above ends primarily my invention consists in such parts and in such combinations of parts as fall within the scope 15 of the appended claims.

In the accompanying drawings which form a part of this specification

Figure 1 is a front perspective view of a 20 case embodying my invention,

Figure 2, a perspective view of the same in an open position, showing in broken lines a document retained therein,

Figure 3, a section of the case taken on 25 line 3—3 of Figure 1,

Figure 4 and 5, fragmentary sections of the case taken on line 4—4 of Figure 1 showing the releasing pin in two different radial positions, and

30 Figure 6, a section taken on line 6—6 of Figure 2.

Like reference characters indicate like parts throughout the views.

As herein shown my case comprises a 35 rectangular front plate or section 10 of thin metal provided with top and bottom flanges 12, and with interspaced lateral hinge sleeves 13 and 14 integral respectively with its opposite edges and directed inwardly

40 therefrom at right angles thereto.

A foldable plate or section 16, also of thin metal and of rectangular shape, and of dimensions which permit it to fit within the flanges 12, has integral with its inner edge 45 interspaced horizontal hinge sleeves 18 alternating with the sleeves 13.

A rear plate or section 20 of rectangular outline and composed of thin metal has top and bottom flanges 22. Formed upon 50 its inner lateral edge are forwardly directed interspaced hinge sleeves 24 alternating with the sleeves 13. Integral with its

opposite lateral edge the plate 20 has a transversely curved resilient flange 25 with its intermediate portion cut away as at 27 55 forming lip portions 28.

In the sleeves 13 and 24 is a hinge pin 30. Rotatably mounted in the sleeves 14 and 18 is a pintle rod 32 provided upon its upper extremity with a flat finger piece 60 34 provided with an opening 35. Near the top and bottom of the rod are lateral pins or projections 37 projecting loosely through horizontally disposed arcuate slots 38.

Integral with the lower edge of the plate 65 16, and with the lower flange 22, are vertically disposed resilient fingers or clips 40 and 41 respectively, having their respective lower portions 42 and 43 inclined. Centrally of the lower flange 12 is a broad resilient vertically disposed and inclined clip 44 with spaced projecting upper end portions 46, and pressing against the plate.

In using my device, the parts being open, 70 as shown in Figure 2, the document positioned as shown at 48 is downwardly inserted between the flanges 22, 10, and 16, and the clips 41, 44, and 40 where it is held by spring pressure against the plates 20, 10 and 16. The plate or wing 16 is then inwardly folded against the back of plate 10, and next the plate or wing 20 is forwardly folded thereover and manually pressed sufficiently to permit the curved resilient flange 25 to snap over and clasp a portion 85 of the rounded side of the case formed by the hinge sleeves 14 and 18. Each portion 28 of the flange overlaps a portion of the adjacent slot 38, and the case with its contents are thus firmly held against unfolding, and the contents protected.

In order to unclasp the parts the operator 90 grasps the finger piece 34 between his thumb and finger and partially rotates the rod 32 bringing the pins 37 against the flange portions 28 as shown in Figure 4. Continued pressure of the pins snaps the flange portions out of engagement with the hinge sleeves, as shown in Figure 5. The case may now be unfolded and the document will be disclosed 95 uncreased and intact.

It is obvious that changes in details of construction within the spirit of my invention may be made. The description of the

device has been given in detail merely for clearness of understanding, and no undue limitation should be understood therefrom.

I claim:

5. 1. In a folding case, a plate, a resilient clip carried by the plate, a second plate connected with one side of the first plate, a resilient clip carried by the second plate, a third plate hingedly connected with the other side of the first plate, and a clip carried by the end of the third plate, said clips all being arranged on the same side of the case when opened and arranged to cooperate with their respective plates to hold a document in the case.
10. 2. In a folding case, a plate, hinge sleeves upon one side of the plate, a second plate, lateral hinge sleeves upon the second plate interengaging with the first sleeves, a hinge rod in the sleeves of both plates, a third plate hingedly connected with the other side of the first plate, and a resilient lateral flange upon the third plate for embracing the sleeves of the first plate.
15. 3. In a folding case, a plate, hinge sleeves upon one side of the plate, a hinge rod in the sleeves, a second plate pivotally mounted upon the rod, a third plate hingedly connected with the other side of the first plate, marginal clips upon all the plates, and a resilient flange upon the third plate for embracing the sleeves.
20. 4. In a folding case, a plate, rearwardly directed flanges upon the ends of the plate, hinge sleeves upon one side of the plate, a hinge rod in the sleeves, a second plate foldable within the flanges and pivotally engaging the rod, a third plate hingedly connected with the side of the first plate opposite the sleeves, forwardly directed flanges upon the ends of the third plate, and a resilient lateral flange upon the third plate for engaging the sleeves, and a resilient marginal clip supported upon one end of the first plate.
25. 5. In a folding case, a plate, hinge sleeves upon one side of the plate, a second plate, lateral hinge sleeves upon the second plate interengaging the first sleeves, a hinge rod in the sleeves of both plates, hinge sleeves upon the other side of the first plate, a third plate, lateral hinge sleeves upon the third plate engaging the second mentioned sleeves upon the first plate, a pintle in the interengaging sleeves of the first plate and third plate, flanges upon the ends of both the first plate and third plate, marginal clips carried by the plates, and a resilient lateral flange

upon the third plate for embracing the first mentioned sleeves of the first plate.

6. In a folding case, a plate, flanges upon the ends of the plate, a resilient clip carried by the plate, rearwardly directed hinge sleeves upon one side of the plate, a second plate foldable between the flanges, a clip upon the second plate, horizontally disposed hinge sleeves upon the second plate, a hinge rod in the sleeves of both plates, a third plate, flanges upon the ends of the third plate, a clip supported by the third plate, rearwardly directed hinge sleeves upon the second side of the first plate, forwardly directed lateral sleeves upon the third plate, a pintle in the last mentioned sleeves and in the second mentioned sleeves of the first plate, and a transversely curved resilient lateral flange on the third plate for embracing the first mentioned sleeves of the first plate, all of said clips arranged to cooperate with their respective plates to hold a document in the case.

7. In a folding case, a plate, hinge sleeves upon one side of the plate provided with horizontal arcuate slots, a second plate, lateral hinge sleeves upon the second plate, a hinge rod rotatably mounted in the hinge sleeves of both plates, a finger piece upon the rod extending beyond the ends of the plates, projections upon the rod extending loosely through the slots, a third plate hingedly connected with the other side of the first plate, and a resilient lateral flange upon the third plate for embracing the first mentioned sleeves and partially overlapping the slots in the path of the projections.

8. In a folding case, a plate, rearwardly directed flanges upon the said plate, hinge sleeves upon one side of the plate provided with horizontal arcuate slots, a second plate, an intermediate lateral hinge sleeve upon the second plate, a hinge rod rotatably mounted in the sleeves of both plates, a finger piece upon the rod extending beyond the plates and provided with a hole, projections upon the rod extending loosely through the slots, a third plate hingedly connected with the other side of the first plate, forwardly directed flanges upon the ends of the third plate, and a curved resilient lateral flange upon the third plate for engaging the first mentioned sleeves and partially overlapping the slots in the path of the projections.

In testimony whereof I have affixed my signature.

ALPHA H. METCALF.
